MACHINE FOR FORMING DECORATIVE ARTICLES

Raimonds Grikis, Chicago, Ill., assignor to CPS Industries, Inc., a corporation of Delaware
Filed Oct. 21, 1964, Ser. No. 405,484
11 Claims. (Cl. 223—46)

This invention relates to mechanical devices adapted for forming decorative articles. More particularly, this invention pertains to new and improved machines adapted for forming decorative bows comprising superimposed loops of strip material, such as ribbon, tape or the like.

There is a continuing and apparently growing demand for pre-formed decorative articles, such as bows, formed of ribbon or similar materials. Such articles have found wide acceptance and use by individual consumers for various decorative purposes, such as in adorning gift packages, as well as in the commercial sales field where they may serve as embellishments on various items. However, to accommodate this demand and its growth, it is necessary to produce such decorative articles in various designs at reasonable prices. This gives rise to concomitant requirements for machines capable of rapidly and economically producing decorative bows. Such machines should be capable of producing articles of a styled, distinctive or individualistic appearance such as is usually associated with bows formed by hand by skilled persons, and preferably in designs not previously provided on a satisfactory mass production basis. However, these machines also should be economical to produce, and simple to operate so that even an unskilled person can consistently and rapidly produce the desired types of articles in completed, ready-to-use form.

One simple bow form which apparently finds ready acceptance in the trade comprises one or more sets of basic folds or loops of ribbon, preferably with loops of varying length, arranged in superimposed pyramid form. Various machines have been proposed for forming this general type of bow, including machines with two sets of fingers having relative interdigital movement, either in a linear or an arcuate path, for forming lengths of ribbon into simple superimposed loops to fabricate such articles. However, such previous machines have evidenced one or more shortcomings such as being difficult and expensive to fabricate and operate, producing bows with undesirable lengths or tails of ribbon, being inflexible and not readily adaptable to the formation of bows of various styles and sizes from ribbon of various widths, producing bows having an unfinished or semi-finished appearance, and/or not including convenient means for securing the formed loops into a complete fabricated article.

It is an object of this invention to provide new and improved bow-forming machines overcoming the aforementioned shortcomings and meeting the above-mentioned requirements.

It will be appreciated, particularly by those skilled in this art that the foregoing is applicable in most respects to both automatic and semi-automatic machines, and that certain basic features of this invention have general application to such various types of machines. At the same time, it is a further object of this invention to fulfill another facet of the general demand for bow-forming machines as noted, and this is a demand for small, simple, inexpensive, semi-automatic machines adapted for consistent, mechanized formation of preformed decorative articles, for instance at the point of sale or in gift wrapping departments of retail stores.

It is another object of this invention to provide improved machines for forming ribbon bows including two or more simple loops of ribbon.

It is another object of this invention to provide ma-

2

chines for simply and inexpensively forming ribbon bows of distinctive, finished appearance.

It is another object of this invention to provide improved machines for conveniently and economically forming completed decorative articles of superimposed loops of ribbon.

It is another object of this invention to provide improved bow-forming machines meeting the aforementioned objects and which are of simple rugged construction, being economical to produce, and which are simple to operate.

Further and additional objects and advantages of this invention will become apparent to those skilled in the art from the drawings, the following description and the appended claims.

In carrying out this invention in one illustrative form, a machine is provided comprising means for supporting a supply of ribbon, a first set of fingers mounted on the machine frame, a movable set of fingers mounted for revolution, in interdigital relation with said first fingers, from one side of said first fingers to the opposite side of said fingers for forming loops of ribbon engaged between said sets of fingers, means adjacent said first fingers and within the arc of movement of said movable fingers for gripping the lead end of a length of ribbon from which such bow is to be formed and being rotatable to form the leading end portion of such ribbon into a closed loop, and securing means cooperative with said gripping means for securing such loops together to form a decorative article.

For a more complete understanding of this invention reference should now be had to the example illustrated in the drawings wherein:

FIG. 1 is a perspective view of a machine employing teachings of this invention;

FIG. 2 is an enlarged top plan view of the machine of FIG. 1, as adjusted for making smaller bows, and with the stapler removed;

FIG. 3 is a rear elevation view of the loop forming mechanism of the machine as in FIG. 2;

FIG. 4 is a partial cross-sectional view taken along line 4—4 of FIG. 2 and looking in the direction of the arrows;

FIG. 5 (sheet 3) is an enlarged cross-sectional view of the center spindle of the machine of FIG. 1;

FIG. 6 (sheet 3) is an enlarged end view of the center spindle of the machine of FIG. 1, with the open position of the clamp shaft shown by the dashed line;

FIG. 7 is a schematic front elevational view of the machine of FIG. 1 with the drive arm in the starting position and ribbon threaded into the machine preparatory to forming a bow;

FIG. 8 is a view similar to FIG. 7, after the loops of the bow are formed and with the stapler in position to secure the loops together;

FIG. 9 is a perspective view of a completed decorative article formed on the machine of FIG. 1;

FIG. 10 is a cross-sectional view of another modification of a center spindle assembly for use in machines as in FIG. 1;

FIG. 11 is an enlarged plan view of the ring-gear and movable arm of the assembly of FIG. 10;

FIG. 12 is a right end view of FIG. 11;

FIG. 13 is a front elevation view of another modification of a bow-forming machine employing teachings of this invention; and

FIG. 14 is a rear elevation view of the loop-bearing mechanism of the machine in FIG. 13.

Referring now to the drawings and more particularly to FIGS. 1, 2 and 3, the illustrated embodiment of the machine 10 includes a base or frame member 12 on which is mounted a ribbon spool support 14, a ribbon guide 16, a loop-forming mechanism 18 and a stapler 20.

The support 14 includes an upright member 22 suitably securing to the base 12, as by spot welding, and a spool engaging element 24. The illustrated element 24 is a piece of flat sheet metal having notches 26 and 28 of various widths formed along one edge to form a retaining support or a guide for ribbon spools of various widths. The guide 16 also includes an upright stand portion 30 suitably secured to the base 12, and a U-shaped element 32 having a pair of guide arms 34 extending transversely of stand 30, across the path of ribbon travel through the machine 10 from a spool on support 14 to mechanism 18, see FIG. 7. A guide pin 36 is secured to stand 30 and extends from the bight portion of the element 32 between and parallel to the arms 34. Each arm 34 is formed with notches 38 and 39, of different widths, in its upper and lower edges, respectively. These notches serve as lateral guides for ribbon of various widths, e.g., $1\frac{1}{4}$ " or $3\frac{1}{4}$ ", which is threaded through the respective notches and around the opposite side of pin 36, see FIGS. 7 and 8.

The loop-forming mechanism 18 includes a pair of fingers 40 and 42 affixed to the upper ends of arms 44 and 46 of a stand 48 adjustably secured to the frame 12. This adjustable securement is obtained by providing a stud 50 fixed to the frame 12 and a thumbscrew 52 which engages a female screw (not shown), in frame 12, together with a series of cooperating, spaced openings 54 in the bottom flange 48a of member 48. Fingers 40 and 42 may be adjusted longitudinally of frame 12 for making bows of different sizes, as will be later described, by removing thumbscrew 52, then moving stand 48 to bring a different pair of openings 54 into registry with the stud 50 and the socket for thumbscrew 52, then replacing the thumbscrew.

Mechanism 18 also includes a U-shaped support 56 which is fixed to frame 12 and supports a rotatable spindle 58, a rotatable drive arm 60, and gears 62a, 62b, 62c (see FIG. 3) for driving the spindle assembly in response to rotation of the arm 60. Referring particularly to FIG. 5, the spindle 58 includes an arbor 64 journaled in the two upstanding legs 56a and 56b of support 56, and a clamp shaft 66 journaled within the arbor and having a lost motion connection therewith. In the illustrated embodiment, this lost motion connection is by means of a transverse pin 68 closely fitting a corresponding opening 70 in the clamp shaft 66 and engaging enlarged openings 72 in the arbor 64.

The drive arm 60 is secured to a drive shaft 74 (FIGS. 2, 3 and 4) that is rotatably supported on legs 56a and 56b beneath arbor 64 and offset slightly towards fingers 40 and 42, relative to the axis of arbor 64, for purposes to be described. Arm 60 includes a curved portion 60a (FIG. 4) of appropriate configuration to extend around arbor 64 when pivoted to the position illustrated in FIGS. 1-4, and a straight portion 60b having openings 78 at appropriate spacings to receive fingers 80 and 82 in positions to intermesh or interdigitate with fingers 40 and 42 (see FIG. 7) at the various settings of stand 48 provided by openings 54. Fingers 80 and 82 may be attached by thumb-screws 84 for ready adjustment to various openings in arm 60.

Referring to FIGS. 2 and 3, gear 62a is drive-connected to shaft 74 and meshes with an idler gear 62b supported on leg 56b, and idler 62b meshes with gear 62c secured to arbor 64 (FIG. 5) to rotate the spindle 58 in response to movement of arm 60 from the position illustrated in FIG. 7 to the position illustrated in FIGS. 1-4 and 6, an arc of about 180° or slightly greater, and the gear ratios are appropriate (2:1) to turn arbor 64 one full revolution during each such movement of the arm 60.

A brake wheel 86 having an annular groove 88 is fixed to clamp shaft 66 by pin 68, and is resiliently engaged by a brake element 90 which comprises a generally U-shaped spring fixed to bar 92 and engaging the annular groove 88. Bar 92 is supported on legs 56a and 56b, see FIG. 2.

The arbor 64 includes a winding section 94 which ex-

tends from leg 56a across the path of movement of ribbon through the machine 10. A guide ring 96 surrounds the base portion of the free winding end 94 of the arbor and is secured to leg 56a, as by spot-welding. An additional, removable guide ring (not shown) may be placed on end 94 against ring 96 when forming bows of narrow ribbon, e.g., ribbon of the width of notches 39.

End portion 94 of the arbor 64 is provided with a slot 98 (FIGS. 1, 2 and 6) communicating with the center bore 100 in this end portion of the arbor, and this portion of the bore 100 receives the closely fitting corresponding end 102 of the clamp shaft 66. End 102 is provided with a flattened or key portion 104 positioned so that the resulting open space thereover in bore 100 communicates with slot 98, note FIG. 7 and the dashed line position of end 102 in FIG. 6, as arbor 64 is rotated clockwise (with reference to FIG. 6), and the inner end of slot 98 is closed by the end 102 as the arbor 64 is rotated counterclockwise, within the range of relative movement permitted by the lost motion connection between arbor 64 and shaft 66. Thus, one end of a length of ribbon may be inserted through slot 98 into bore 100 when the inner end of the slot 98 is open. Thereafter, as the spindle is driven counterclockwise by driving arbor 64, the ribbon will be engaged between the corner 104a on clamp shaft 66 and the opposing corner of arbor 64 at the inner end of slot 98 due to the retaining action of element 90 on clamp shaft 66 and the lost motion connection between arbor 64 and shaft 66.

The stapler 20 is pivotally mounted at 106 on a stand 108 which is secured on frame 12. The stapler is movable from a retracted position as illustrated in FIG. 1 to a position over winding end 94, as in FIG. 8, wherein the staple-driving mechanism cooperates with a pair of anvil slots 110 in the spindle for driving and clinching staples. A guide member 112 may be secured to stand 108. Member 112 includes spaced guide arms 114, one on each side of the stapler 20, to guide the stapler as it is pivoted to its stapling position in registry with the slots 110.

In the operation of the machine 10, a ribbon supply, such as a ribbon spool S is mounted on support element 24, see FIGS. 7 and 8. The stapler 20 is moved to its retracted position and arm 60 is moved to its initial position as shown in FIG. 7. Movement of arm 60 to this position drives arbor 64 to position the spindle as shown in FIG. 7, with the inner end of slot 98 open, and positions pins 80 and 82 beneath pins 40 and 42 on either side of arm 44. The precise initial angular positions of arm 60 and of spindle 58 are not critical, and in fact will vary somewhat according to the position of stand 48. Positioning fingers 80 and 82 well below fingers 40 and 42 facilitates positioning the ribbon therebetween. Referring to FIG. 7, the ribbon R is threaded through the notches 38 or 39, depending upon its width, and around the opposite side of pin 36, between the two sets of fingers 40-42 and 80-82, and the distal end of the ribbon is inserted through slot 98 into bore 100, over the flat face 104 of clamp shaft 66. Thereafter arm 60 is rotated in a counterclockwise direction by the operator, as by grasping the end of elongated pin 82, to move the pins 80 and 82 counterclockwise along their paths of revolution about the axis of shaft 74. Pins 80 and 82 thus move upwardly through a position of interengagement with pins 40 and 42 to engage the ribbon positioned between the two sets of pins, and draw the ribbon into loops as illustrated in FIG. 8 as the pins 80 and 82 are moved to their left end position. Simultaneously, the rotational movement of arm 60 operates gears 62a-c to drive arbor 64 and rotate spindle 58 through one revolution, counterclockwise in FIG. 8, to form a closed or 360° loop of ribbon around arbor 64. The lost motion connection between arbor 64 and clamp shaft 66, together with the braking effect of brake element 90, insures sufficient relative movement between the arbor 64 and

shaft 66 to grip and retain the distal end portion of the ribbon between the arbor and the closely fitting corner 104a. Rotation of spindle 58 thus draws the ribbon through the machine, around the forming pins, during the loop-forming operation. The forming pins 40, 42, 80 and 82, and pin 36, are provided with smooth, low friction surfaces, or may comprise rollers, to facilitate this loop-drawing operation. The positive, direct gear drive 62a-c between arm 60 and arbor 64, together with a fixed stop position of arm 60 (with the curved portion 60a engaging arbor 64 as in FIG. 4), insure that slots 110 are at the top of arbor 64 in position to cooperate with stapler 20 for applying staples to the looped ribbon after the loops are formed.

Referring to FIGS. 7 and 8, it will be observed that the ribbon is disposed over anvil-slots 110 in inserting the distal end into slot 98. This disposition of the end of the ribbon, and subsequent rotation of spindle 58, forms a circle or 360° loop L_1 of the ribbon R with overlapping ends of this loop disposed over slots 110. Also, the loops L_2-L_5 formed by fingers 40, 42, 80 and 82 are positioned with the overlying connecting leg portions of successive loops disposed over slots 110 as in FIG. 6. Thereupon, the stapler 20 is pivoted into registry with slots 110, and a staple T (FIG. 9) is applied by the stapler against the bottom of the anvil slots 110 to secure the juxtaposed legs of the ribbon loops together and to retain the loops in a decorative article or bow. Prior to driving the staple, appropriate bow-mounting means may be positioned over the formed loops to be secured to the loops by the application of the staple or other securing device. Such bow-mounting means may comprise a paperboard element M (FIG. 9) having a coating of pressure-sensitive adhesive and a protective, removable covering therefor on one side, or a length of tie-string, or other appropriate securing means.

Fingers 80 and 82 are in alignment with fingers 40 and 42 when in the end bow-forming position illustrated in FIG. 8, and the fingers are slightly below the top of spindle 58 to properly position the ribbon against the spindle. Further, the spindle, and particularly the stapling slots 110, are centered between fingers 42 and 80 whereby a balanced symmetrical decorative article B, FIG. 9 is formed when the staple is applied. This balanced result, together with the interengaging or interdigital relation of pins 40, 42, 80 and 82, is obtained in the illustrated machine by mounting arm 60 for pivotal movement about an axis offset from the perpendicular bisector of lines joining pins 40 and 42 and the final positions of pins 82 and pin 80 (left end position as in FIG. 8), respectively, e.g., offset toward finger 42 from a vertical plane through the axis of spindle 58, as seen in FIG. 2.

After the staple T is applied, the stapler is raised, arm 60 is moved clockwise to release the clamped leading end of ribbon R, and the ribbon is severed between the completed article and the supply S. Thereupon the completed article B is removed and arm 60 is returned to its starting position for forming the next article.

Bows having loops L_2-L_5 of various lengths can be produced by varying the spacing of fingers 40, 42, 80 and 82 from the spindle 58. In the illustrated embodiment 10 this is accomplished by adjusting stand 48, relative to spindle 58, on mounting stud 50 and thumbscrew 52, and moving fingers 80 and 82 to corresponding openings 78 in arm 60.

Another spindle assembly and drive means for a machine 10 is illustrated in FIGS. 10-12. In this construction, a ring gear 120 is formed with or secured to the arm 122 which receives the loop forming pins (not shown). Ring gear 120 engages a gear 124 affixed to the arbor 126. A brake wheel 128 is secured to the clamp shaft 130 and is engaged by braking element 132 mounted on bar 134. Arm 122, and gear 120, are supported on

bearing 136 which is journaled on bar 132. A lost motion connection between arbor 126 and clamp shaft 130 is effected by a pin 138 secured to gear 124 and arbor 126 and extending through an opening 140, of substantially greater diameter than the pin, in clamp shaft 130. The winding section of this assembly is the same as spindle 58, as indicated by the application of the same members to corresponding elements.

Referring now to the embodiment illustrated in FIGS. 10 and 14, the machine 150 includes many elements corresponding to elements already described regarding machine 10, but is provided with separate drive means for the spindle assembly and the movable forming fingers. In this embodiment the ribbon supply support 152 includes a generally cylindrical spool-engaging element 154 having slots 156 and 158 of varying widths and depths formed in the upper surface. The guide 160 includes a stationary block 162, a pivotally-mounted, weighted block 164 and a pin 166. The stationary forming fingers 168 and 170 are mounted on arms 170 and 172, which are individually adjustable in a slot 174 on a center spindle support 176. Movable fingers 178 and 180 are similarly adjustably mounted in a slot 182 on a pivotally mounted arm 184. Arm 184 is moved in the same manner as arm 60 of machine 10 to form loops of ribbon in producing a decorative article. However, a separate drive is provided for the spindle assembly 186.

The spindle assembly 186 includes an arbor 188 with a slot 190, and a clamp shaft 192 provided with a slot 194 to selectively communicate with slot 190, within the range of motion of a lost-motion connection (not shown) between arbor 188 and shaft 192, for gripping the ribbon end. In the illustrated embodiment, machine 150 is adapted for rotation of the spindle assembly 186 by driving the clamp shaft 192, to provide the self-energizing gripping action more fully described below with reference to machine 10. The drive means for rotating the clamp shaft, and thus the spindle assembly, comprises a hand wheel 196 affixed to a shaft 198 on which is mounted a gear 200 which meshes with a gear 202 on the clamp shaft 192 (see FIG. 12). Appropriate stops, such as a ball or pin and detent (not shown) may be provided to limit the rotation of wheel 196 to that rotation necessary to insure registry between stapling slots (not shown) in arbor 188 and a staple driver 204.

The machine 150 is operated in substantially the same manner as outlined above regarding machine 10, except that separate operations are required to rotate wheel 196 and form a center loop L_1 on spindle assembly 186, and to move arm 184 to form loops L_2-L_5 between fingers 168, 170, 178 and 180. The center loop is normally formed first.

Bow-forming machines have thus been provided which are of simple rugged construction, and which are easy and simple to operate, even by unskilled persons, to consistently produce bows having an individualistic finished appearance. The illustrated embodiments are economical to construct and operate and are designed to conveniently produce bows with superimposed loops of varying lengths, and a closed center loop, in a completed decorative article of distinctive bow design. Further, these machines are readily adapted to formation of bows of various styles and sizes, utilizing ribbon of various widths.

It will be obvious that other modifications of the specific embodiments illustrated may be made without departing from the spirit and scope of this invention, particularly by those skilled in the art in light of the foregoing teachings. For example, and not by way of limitation, the clamping motion between arbor 64 and shaft 66 can be made self-energizing by driving the clamp shaft directly instead of the arbor, e.g., by mounting gear 62c on an extended end of the clamp shaft instead of on the arbor, reversing the size relationship of holes 70 and 72 relative to the pin 68, and repositioning shaft 66 for clamping engagement between the edge 104b and the

opposing corner of arbor 64 at the inner end of slot 98 within the range of lost-motion movement. Further, more or less loop forming fingers may be provided in each set, various drive arrangements, either manual or automatic, separate or integrated, and various ribbon feed and gripping mechanisms, may be added or substituted for those illustrated herein, particularly if it is desired to design an automatic machine, while retaining various features of the invention.

While particular embodiments of the invention have been shown, it will be understood, of course, that the invention is not limited thereto since modifications may be made by those skilled in the art, particularly in light of the foregoing teachings. Therefore, it is contemplated by the appended claims to cover any such modifications as incorporate those features which may be said to constitute the essential features of this improvement, within the true spirit and scope of the invention.

I claim:

1. A machine for forming decorative articles comprising a frame, a first set of fingers mounted in a fixed position on said frame, a second set of fingers, a movable support element mounting said second set of fingers for movement in interdigital relation with said first fingers from a first position at one side of said first fingers, through a position of interengagement with said first fingers, to a second position on the opposite side of said first fingers to draw ribbon engaged between said fingers into loops of varying length, and first means between said first set of fingers and said second position for retaining an end of such ribbon engaged between said fingers during such movement of said movable fingers.

2. A machine as in claim 1, wherein said first means is rotatable, and including drive means actuated by movement of said movable fingers from said first position to said second position to rotate said first means.

3. A machine as in claim 2 and wherein said rotatable first means includes a pair of concentric members having relative movement for engaging such end of ribbon.

4. A machine as in claim 3 and including a lost motion connection between said pair of members.

5. A machine as in claim 1, wherein said first means comprises a pair of closely fitting concentric members mounted for relative rotative movement with respect to one another and formed with openings and cooperative engaging portions to receive and grip such end of ribbon upon such relative movement, said concentric members being mounted for conjoint rotation to form the end portion of such ribbon into a loop, drive means connected to one of said concentric members for effecting such rotation, and means for retarding the rotation of the other of said concentric members to effect such relative rotative movement.

6. A machine for forming decorative articles comprising a frame, a first set of fingers fixed on said frame, a ribbon supply support fixed on said frame on one side of said first fingers, an arm mounted on said frame for pivotal movement about an axis adjacent said first fingers and on the side thereof opposite said support, a plurality of fingers mounted on said arm for revolution in interdigital relation with said first fingers from a first position on one side of said first fingers, through a position of interengagement with said first fingers, to a second position on the opposite side of said first fingers as said arm is pivoted to form first loops from ribbon positioned between said fingers when said arm is in said first position, a rotatable ribbon gripper disposed between said axis and the path of movement of the movable finger nearest said axis, and between said first fingers and said second position of said movable fingers, means operable upon movement of said arm for rotating said gripper to form a closed loop, and means cooperative with said gripper for securing such first loops and closed loop together to form a decorative article.

7. A machine for forming decorative articles comprising means for gripping an end of a length of ribbon, a first finger, a movable support element mounting said first finger for movement along an arcuate path about said gripping means from a first position at one side of said gripping means to a second position at another side thereof, and a second finger mounted in a fixed position on said one side of said gripping means between said gripping means and the portion of said path of said first finger adjacent said first position, said gripping means being disposed generally on the perpendicular bisector of a line joining said second finger and said first finger when said first finger is in said second position, said first finger being mounted to provide said movement along a path of revolution about an axis which is offset towards said second finger from said perpendicular bisector and of a radius whereby said first finger and said second finger are spaced substantially equal distances from said gripping means when said first finger is in said second position, whereby a length of ribbon having one end engaged by said gripping means and extending between said fingers and across said path of movement of said first finger when said first finger is in said first position may be formed into loops of substantially equal lengths of extension from said gripping means as said first finger is moved along said path to said second position.

8. A machine as in claim 7 and including means cooperative with said gripping means for securing loops formed by said fingers together.

9. A machine for forming decorative articles comprising rotatable means for gripping an end of a length of a ribbon and forming the end portion of such ribbon into a closed loop, a first set of fingers mounted in a fixed position on one side of said rotatable gripping means, a second set of fingers, a movable support element mounting said second set of fingers for movement along an arcuate path from a first position at said one side of said gripping means and at one side of said first fingers, through a position of interdigital engagement with said first fingers, to a second position on the opposite side of said rotatable means to draw ribbon engaged between said fingers into loops of varying lengths and position said loops adjacent said rotatable means.

10. A machine as in claim 9, and including means cooperative with said gripping means for securing said loops formed by said rotatable means and said fingers together.

11. A machine for forming decorative articles comprising a support frame, a ribbon supply support on said frame, means mounted on said frame for gripping an end of a length of a ribbon and rotatable to form the end portion of such ribbon into a closed loop, a first set of fingers fixed on said frame between said rotatable gripping means and said supply support, a second set of fingers, a movable support element mounting said second set of fingers for movement along an arcuate path from a first position at said one side of said gripping means and at one side of said first fingers, through a position of interdigital engagement with said first fingers, to a second position on the opposite side of said rotatable means to draw ribbon engaged between said fingers into loops of varying lengths and position said loops adjacent said rotatable means.
